BEVERAGE DISPENSER

George E. Seener, St. Louis County, Mo., assignor to Multiplex Faucet Company, St. Louis, Mo., a corporation of Missouri

Filed Aug. 17, 1959, Ser. No. 834,188
4 Claims. (Cl. 222—129.1)

This invention relates to beverage dispensers, and more particularly to that form of beverage dispenser which has a separate source for each of the syrup and carbonated water.

An important object of the present invention is to provide a beverage dispenser having flow control means which retains substantially the amount of carbon dioxide as originally added to the water, but which yet limits the amount of effervescence of the carbonated water at the flow nozzle and further preserves the proper mixture of syrup and carbonated water. This control of the carbonation is made possible through a novel valve and stream straightener combination.

Another object of the invention is to provide a beverage dispenser which incorporates improved cooling characteristics with a minimum of refrigeration loss. According to the present invention, the nozzle and its handle incorporate a minimum of metal located externally of the cabinet.

Still another object of the invention is to provide a beverage dispenser having an improved means for interconnecting the nozzle and valve means with the syrup and water sources. Thus in the present invention, the nozzle and valve means are wholly located beneath the wall of the container, connected directly to the cooling coil in the aluminum floor casting, thereby eliminating the necessity of cutting through a side wall of the container for external location of the operating handle. This feature eliminates more than a minimum loss of the cooling accomplished within the casting and prevents the escape of carbon dioxide gas which ordinarily accompanies the heating of a beverage.

Another object of the invention is to provide a beverage dispenser which is very sanitary and easy to clean.

Still another object of the present invention is to provide a beverage dispenser which is inexpensive to manufacture.

Additional objects will be apparent from the following description of the invention.

In the drawings:

FIGURE 1 is a front elevation view of the beverage dispenser;

FIGURE 2 is a view in section taken along the lines 2—2 of FIGURE 1;

FIGURE 3 is a view in section taken along the lines 3—3 of FIGURE 1;

FIGURE 4 is a view in section taken along the lines 4—4 of FIGURE 1;

FIGURE 5 is a view in section similar to FIGURE 2 but enlarged to show only the relation of the container with the container top;

FIGURE 6 is a partial view in section, also enlarged, showing the rear of the top as placed upon the container;

FIGURE 7 is a partial view in section showing the lower front area of FIGURE 2 on enlarged scale.

FIGURE 8 is a partial view in section showing the syrup float control;

FIGURE 9 is a partial view in section showing the lower front area of FIGURE 4 on an enlarged scale and with a section taken through the syrup path;

FIGURE 10 is a partial view in section similar to FIGURE 9, but with a section taken through the path of carbonated water;

FIGURE 11 is an enlarged view in section of a portion of the water side of the valve;

2

FIGURE 12 is a partial view in section taken along the lines 12—12 of FIGURE 9;

FIGURE 13 is an enlarged view in section of the stream straightener insert;

5 FIGURE 14 is a bottom view of the valve box;

FIGURE 15 is an end view of the valve box taken from the right side of FIGURE 14;

FIGURE 16 is a plan view of the syrup orifice disk;

FIGURE 17 is a view in section of a modification, similar to the view of FIGURE 9;

FIGURE 18 is a view in section of the modification, similar to the view of FIGURE 10;

FIGURE 19 is an enlarged view in section of a portion of the water valve of the modification; and

FIGURE 20 is an end view of the valve box used in the modification.

The housing 20 of the present invention is illustrated as being generally rectangular in shape. The housing 20 is provided with a sheet metal base 21, preferably of chrome for rust resistance and ease of cleaning. The base 21 comprises a continuous strip of sheet metal bent to conform to the bottom of the housing 20, as illustrated, and having its ends 22 and 23 terminated in separated relationships (as can be seen at FIGURE 1).

25 The base 21 has flanges 24 by which it may be attached to the housing 20 in a well known manner, as by screws. The lower end of the base 21 also has flanges 25. A plurality of grommets 26 are attached to the flanges 25 to provide scratch eliminating feet to the dispenser. A brace 30 27 connected between the sides adds rigidity to the base 21.

The base is completed by the attachment of a chrome plate 28 between the ends 22 and 23 of the strip 21.

The exterior of the housing 20 includes a flat plate 35 bottom 30 to which the flanges 24 of the base 21 are attached.

The bottom plate 30 has a flange 31 turned downwardly about most of its perimeter. It will be observed that the bottom plate 30 is cut away at its front edge 32 so that it can cooperate with other parts to form a flat recess as will appear.

40 The outer sides of the housing 20 are composed of a single, continuous metal sheet 33. The lower end 34 of the sheet 33 extends even with the flanges 31 on the bottom plate 30. The flanges 31 are welded to the sheet 33. As can be seen in FIGURE 1, the sheet 33 has a trapezoidal cut-out 35 at its front.

A sheet metal connection is made between the front side 33 and the bottom plate 30 as can be seen from FIGURES 1 and 2. This connection is in the form of a step comprising a horizontal plate 36 and a vertical plate 37, which cooperate to form a recess 38 at the front of the cabinet for receiving the nozzle structure to be described. The stepped sections 36 and 37 of the recess 38 have portions 55 cut away (which are not visible because they are hidden by the nozzle structures) so that certain connections can be made through the housing.

A rubber or plastic channel-shaped border is glued to the juncture of the flange 31 with the side wall 33. The rubber channel 39 affords protection against any possible sharp edges at that juncture. The channel 39 also serves as a bumper against glasses shoved against the housing.

60 The interior of the housing includes a cast aluminum cold plate 43. The cold plate 43 has a flat top 44, which is the floor of the housing. There is a continuous flange 45 connected to the floor 44. The lower surface of the casting 43 has the irregular configuration, illustrated in FIGURES 2, 3 and 4, and will be more fully described in conjunction with the parts which mate with the various irregular sections of the casting 43.

65 A continuous inner wall 48 is attached by screws 49 to

the flange 45 of the casting 43. The inner wall 48 is spaced from the outer wall 33 as illustrated. The inner wall 48 is of stainless steel sheet metal construction, which is less expensive than aluminum. At the juncture of the inner wall 48 with the flange 45, in addition to the screws 49, a metal adhesive provides a water tight connection. Such adhesive is conventional.

The space at the top between the outer wall 33 and the inner wall 48 is spanned and closed by a continuous channel member 50 secured to each of the walls. A rubber molding 51 of the general cross-sectional shape illustrated in FIGURES 5 and 6 covers the top of the wall. The space between the walls 33 and 48 is filled with a well known insulating material 52, such as fibre glass or wall insulation.

A top 53 for the housing 20 is formed of a bent plate having a rubber molding 54 covering its continuous lower edge. The rubber molding 54 seats upon the molding 51 when the top 53 is placed upon the housing 20. A handle 55 attached to the top 53 provides means for removing the top 53.

There is provision for two syrup containers in the present embodiment. Inasmuch as both containers and their dispensing machine are the same, only one will be described.

There is a round hole 60 through the cold plate casting 43 to permit passage of an irregular shaped bushing 61. The bushing 61 projects both below the cold plate 43 and above it, and has a recess 62 through the top to receive the syrup dispenser. The bushing 61 is threaded at its lower end 63 for engagement with a valve housing which will be described. An O ring 64 provides a fluid-tight seal with the valve housing. A shoulder 65 separates the lower portion from the upper portion of the bushing 61. The upper portion is somewhat larger in diameter than the lower portion 63 and has external threads 66 so that a threaded ring 67 having ears 68 can be manually turned onto the upper portion 66 of the bushing 61. When the bushing 61 has been threaded into the valve housing, the washer 67 is turned onto the upper threaded section 66 and tightened against the floor 44 of the cold plate 43. This tightly secures the bushing 61. There is a rubber washer 69 between the washer 67 and the cold plate floor 44.

The syrup container 70 can be seen in FIGURES 2 and 3 as comprising two separate sections 71 and 72. The larger section 71 has a top 73 on it, and is formed integrally with the smaller, lower section 72. Between the sections 71 and 72, there is an annular shoulder 74. The lower section 72 has a small, circular spout 75 at the forward end of its bottom surface. The spout 75 fits within the recess 62 of the bushing 61.

A float assembly 76 sits upon the annular shoulder 74. The float mechanism 76, which is not a part of the present invention, comprises a rubber seal 77 seated upon the annular shoulder 74. The seal 77 has a vent tube 78 passing through it.

There is another hole 79 through the seal 77. A shaft 80 is freely reciprocable through the hole 79 and has a stop washer 81 at its top to limit the downward reciprocation of the shaft 80. The lower end of the shaft 80 has an enlarged conical shape 82 which will not pass through the hole 79 but will seal that hole against fluid passage when seated in the bottom of the hole 79. Attached to the shaft 80, adjacent the enlarged section 82 is a float 83. The float 83 will, when in a lowered position, permit syrup to flow into the lower chamber 72. When enough syrup has entered the lower chamber 72 that the float 83 rises seating the conical portion 82 within the hole 79, the flow of syrup will be blocked through the hole 79. At that time, a predetermined head of syrup will exist over the lower spout 75, thereby affording a uniform rate of syrup flow for every syrup dis-

10 pensing operation. The tube 78 is a breather tube to permit air to escape as the lower chamber 72 fills each time.

As before mentioned, the syrup spout 62 opens into a bushing 61, which in turn is threaded into a valve housing 85. That valve housing 85 is illustrated in FIGURES 14 and 15 as being of generally rectangular shape. There are two valve provisions within the housing, one for the syrup and one for the carbonated water. The one for the syrup will be described first with particular reference to FIGURE 9.

There is a chamber 86 communicating with the threaded opening 63 in the valve housing 85. The rear end of the recess 86 has an access opening 87. The opening 87 has threads 88 for engagement with a closure cap 89. The closure cap 89 has a spring seat 90 on it.

There is a long bore 91 extending from the recess 86 to the front end 92 of the valve housing 85. The bore 91 also communicates with a downwardly extending recess 93 which opens into the bottom 94 of the valve housing 85. The recess 93 has an annular flange 95 about its periphery. The flange 95 has external threads 96 upon which a retainer 97 is threaded. The retainer 97 holds an orifice washer 98 between it and the flange 95. The orifice washer 98 has a small hole 99 through it and through which the syrup passes. The washer 98 is readily replaceable by different washers having different sized orifices.

A piston 103 is reciprocable within the bore 91. The piston 103 has one end 104 enlarged so as to fit fairly tightly within the bore 91 and has a provision for an O ring 105 to provide a fluid type seal of the enlarged end 104 within the bore 91. The end 104 has a generally semi-hemispherical shaped end 106 which extends outside of the valve housing 85.

A slender stem 107 extends between the end 104 and the opposite end 108 of the piston 103. With reference also to FIGURE 11, the end 108 has a frusto-conical section 109 extending from the slender rod portion 107 to a maximum diameter slightly less than the diameter of the bore 91. An annular flange 110 is spaced from the frusto-conical section 109 by a peripheral groove 111 in the end 108. A cylindrical stud 112 cooperates with the flange 110 to define a spring seat 113 on the end 108 of the piston 103.

There is a resilient sealing washer 114 seated in the groove 111. A compression spring 115 extends between the spring seat 90 on the cap 89 and the spring seat 113 on the end 108 of the piston 103. The spring 115 tends to continuously urge the piston 103 forward within the bore 91 causing the seal 114 to normally seal off the recess 86 from the bore 91 against passage of syrup. When the piston 103 is moved rearwardly by a force against the forward end 106 (in a manner to be described) the seal 114 breaks contact with the wall of the recess 86 so that syrup can pass from the recess 86 through the bore 91 into the recess 93 and through the orifice 99 of the washer 98. The rate of flow of syrup through the orifice 99 will always be the same, drink after drink, because of the constant head of syrup above the syrup spout 75.

The carbonated water dispensing mechanism will now be described, with particular reference to FIGURES 10 and 13. (It is here to be observed that while the present embodiment is illustrative of a dispenser having separate valve means for each of the syrup and the water, the concept is equally applicable to premix dispensers, that is, those in which the water and syrup are mixed before reaching the valve. For such dispensers, the same valving and stream straightener arrangement could be used as is here described, while the separate syrup valving could be eliminated.)

A spiral tubing 120 is cast within the cold plate 43. A carbonated water inlet 121 is connected to one end of the coil 120 (FIGURES 1, 2, and 7). Thus, the carbonated water to be dispensed will circulate through the

coil 120 so that it will be cooled by the ice which will have been placed within the housing 20.

A block 125 having a machined recess 126 is fitted within the cold plate casting 43, as illustrated in FIGURES 9 and 10. The end of the tubing 120 not connected to the inlet 121 connects to a water outlet 127 within the block 125. The outlet 127 communicates with the recess 126.

The valve mechanism for the carbonated water which communicates with the recess 126 is similar to that for the syrup. As can be seen in FIGURE 10, there is a piston 128 having an enlarged forward end 129 with an O ring seal 130 for retaining liquid within the housing. The piston 128 is reciprocable within a bore 131 in the valve housing 85, and has the frusto-conical end 132, a resilient sealing washer 133 and a spring seat 134.

Communicating with the recess 131 is a larger recess 135 opening to the back of the valve housing 43. The opening has threads 136 for a threaded engagement with a sealing cap 137. The sealing cap 137 has an O ring seal 138 between it and the recess 135. A compression spring 139 biases the piston 128 forwardly within the housing 43.

The closure cap 137 has an elongated end 140 of reduced diameter carrying an O ring seal. There is an orifice 141 through the length of the cap 137, communicating the recess 135 with the end 138 of the cap 137. The orifice 141 being of smaller diameter than that of the cooling coil 127 serves to reduce pressure of the water within the recess 135. This reduction in pressure partially conditions the water for being dispensed in a soft stream form as will be hereinafter explained in conjunction with a discussion of the stream straightener.

The reduced end 140 of the cap 137 is of a size to fit tightly within the recess 126 of the insert block 125. When so positioned, the O ring on the end 140 provides an effective seal against the passage of fluid so that all fluid which passes from the opening 127 will be through the elongated orifice 141.

Referring to FIGURE 13, there is a hole 143 through the bottom of the housing 85 and opening into the bore 131. The upper end of the hole 143 has a peripheral lip 144. The lower end of the hole 143 comprises an annular flange 145 threaded to receive a water straightener retainer 146. The inner diameter of the retainer 146 is somewhat less than the diameter of the hole 143. The difference between the two diameters defines a shoulder or rim 147. A cylindrical bushing 148 is seated upon the shoulder 147, and extends upwardly within the hole, terminating short of the rim 144.

A stream straightener 150 is retained between the bushing 148 and the rim 144. The stream straightener has an elongated orifice or tube 151 extending vertically from its upper end, and terminating at 152 short of its lower end.

The diameter of the stream straightener below the portion resting between the bushing 148 and the rim 144 is considerably reduced, as at 153. It is within this reduced section 153 that the orifice 151 terminates.

There are two horizontal orifices 154 and 154' communicating with the end 152 of the first orifice 151. The orifices 154 and 154' are at right angles to each other and generally at right angles to the first orifice 151. All orifices are of approximately the same diameters, although this is not necessary.

The lower end 155 of the stream straightener 150 is in the form of an inverted frusto-conical configuration. This lower end 155 cooperates with the inner wall 156 of the retainer 146 to define a restricted opening 157.

It can be appreciated that the path of carbonated water will be through the water inlet 121 to thereafter circulate through the spiral coil 120. The water then reaches the end 127 of the coil 120 and passes through the orifice 140 in the closure cap 137. If the piston 128 has been moved rearwardly within the valve housing 43, the seal 133 will

have been separated from the valve housing permitting the water to flow past the recess 135 into the bore 131. From the bore 131, the water passes through the orifice 151, through the orifices 154 and 154', and then is sprayed into the frusto-conical shaped end 155 of the stream straightener 150. It has been found that for a water source pressure of from 70 to 120 p.s.i., the present valve and stream straightener arrangement will reduce the rate of flow to 5 ounces per four seconds. This reduction in the flow of carbonated liquid greatly reduces the effervescence of the liquid as it is dispersed from the stream straightener, thereby permitting a greater volume of beverage to be dispensed into a glass.

The bottom of the valve housing 43 has an annular lip 160 surrounding both the syrup and the carbonated water outlet. A mixing bowl 161 of the shape clearly illustrated in FIGURES 9 and 10 is pressfit onto the lip 160. The mixing bowl 161 has a ribbed opening 162 in its bottom through which the mixed fluid may pass. Fluid from the syrup outlet and the carbonated water outlet passes into the mixing bowl and is well mixed before passing through the outlet 162 into a glass.

A common operating handle 165 operates both syrup and carbonated water valve pistons. The handle 165 is pivoted at 166 about two spring biased pins 167. The handle 165 has a turned up flange 168 extending the width of the handle, so that when the handle is pivoted in the direction of the arrow about the pins 167, the flange 168 will force the valve pistons 103 and 128 toward the rear of the valve housing, for a dispensing operation in the manner before described.

It will be observed that in the present arrangement the valve housing 85 is located entirely beneath the housing walls, and has its openings communicating only with the cold plate 43. Thus, boring through housing is eliminated.

In operation, the syrup container 70 is filled with syrup and the housing around the containers is filled with crushed ice or ice cubes. Carbonated water is made available to the inlet 121 of the coil 120.

The float arrangement 76 of the syrup container 70 assures that a predetermined head of syrup will be provided above the container spout 75.

When the handle 165 is pivoted about the pins 167 the flange 168 forces the valve pistons 103 and 128 rearwardly in the housing to cause both the syrup and the carbonated water to be delivered to the mixing bowl 161 as before explained. The mixture of syrup and carbonated water then passes through the outlet 162 in the mixing bowl 161 to a glass held beneath the mixing bowl.

FIGURES 17 through 20 illustrate a modification of the invention which may be employed for a different housing arrangement. The essential elements and operation of the modification are the same as has been described for FIGURES 1 through 16.

In this modification the housing 200 has a cold-plate 201 which is flatter than the cold-plate previously described. The syrup container 202 has its outlet spout 203 protruding through the cold-plate 201.

The valve box 204 has the general shape illustrated in FIGURES 17, 18 and 20. This may be compared to the valve box or housing 85 shown in FIGURES 9, 10, 14 and 15. For the syrup side there is threaded into the syrup end of the valve box a communicating tube 205, having suitable O-ring sealing means 206 and 207. The communicating tube 205 has a passage 208 through it which communicates with the syrup spout 203 by means of a chamber 209 formed in an insert 210 in the cold-plate 201.

The housing 204 has two chambers or bores 211 and 212. In the chamber 211 is a piston 213, spring urged by a compression spring 214 in the manner already described for the previous modification, which upon being forced to the right by the operating handle 215 will un-

seat the sealing ring 216, thereby permitting syrup to flow past the valve.

There is an orifice disc 217 having a small orifice 213 through which the syrup must pass before reaching the mixing bowl 219. The orifice disc is held to the valve box 204 by a threaded retaining cap 228, having a large hole 221 in it, secured to a threaded extension 222 at the bottom of the valve box 204.

The water valve has the same basic elements as that of the first modification. There is a piston 223 reciprocable in the chamber 212 for introducing carbonated water to the stream straightener 224. (The stream straightener 223 is similar to that shown in FIGURE 13 and described infra.) The stream straightener 224 is held to the valve box 204 by a retainer 225 threaded onto a projection 226 beneath the valve box 204.

There is a tubular communicating connection 227 between the chamber 212 and the water source 223. The inner end 229 of the communicating means 227 has a Hayes Diaphragm assembly 239, which is schematically illustrated at FIGURE 19 and which of itself is not a part of the present invention. The Hayes Diaphragm is employed to maintain a constant water pressure to the valve 228, regardless of varying pressures at the water source.

It will be observed that the essential difference between the two modifications of the invention described is that the valve arrangement of the modification of FIGURES 17 through 20 is located entirely forward of the housing, whereas the valve and nozzle arrangement of the first described embodiment is located partially beneath the housing and container.

Various changes and modifications may be made within the process of this invention as will be readily apparent to those skilled in the art. Such changes and modifications are within the scope and teaching of this invention as defined by the claims appended hereto.

What is claimed is:

1. A beverage dispenser comprising a housing having a cast floor, a front wall and side walls attached to the floor; a syrup source; passage means opening into the casting and connected to the syrup source for passage of syrup through the casting; a water source; passage means opening into the casting and connected for passage of water through the casting; the syrup and water passages having openings next to one another adjacent the front end of the floor and a discharge nozzle connected into the casting below the front wall, the discharge nozzle having ports in its rearward side for connecting to openings in the syrup passage means and the water source passage means; the discharge nozzle having an outlet through its lower side and having passages through it for communicating the ports with the outlet; valve means in each passage and a lever for opening and closing the valve means; the lever being positioned forward of the front side of the housing.

2. In a beverage dispenser having means for dispensing syrup into a mixing bowl at a constant flow rate for successive drinks: a carbonated water source; a valve between said source and the mixing bowl; a stream straightener between the valve and the mixing bowl; said valve, when opened, admitting water from said source through said stream straightener; said stream straightener having a first tube through which the water first flows and a second tube angularly communicating with the first tube for changing the path of flow of the water as it leaves the first tube, a skirt below the second tube onto which water passing from the second tube falls; the axis of the second tube being substantially perpendicular to the direction of flow of water past the skirt; and means for restricting the flow of water past the skirt.

3. A stream straightener for a carbonated beverage dispenser; said stream straightener being connected to a carbonated liquid source; said stream straightener comprising a small passage for directing the flow of liquid in one direction and opening into another passage for directing the flow of fluid in a second direction; said second passage opening above a skirt portion of inverted frustoconical shape, the lower periphery of which cooperates with a cylindrical surface to define a restricted annular opening, the inner edge of the surface of the skirt portion being positioned immediately below the second passage opening with the outer edge of the skirt portion positioned below and outward of the inner edge and below the restricted annular opening, the axis of the second passage being at substantially right angles to the direction of fluid flow past the skirt, the cylindrical surface extending upwardly from the restricted opening to a point opposite the second passage opening in the path of fluid from the second passage.

35 4. The stream straightener of claim 3 wherein the orifices and the skirt portion are replaceable within the cylindrical surface to permit modification of the stream straightener characteristics.
